ATTACHMENT FOR PREVENTING IDLE FILLING THREADS FROM ENTERING CLOTH ON MULTIPLE SHUTTLE LOOMS

Joseph Francis Muheim, Providence, R. I., assignor to Henry Owens & Company, Inc., Providence, R. I., a corporation of Rhode Island

Application January 1, 1942, Serial No. 425,360

18 Claims. (Cl. 139—116)

My invention relates to improvements in an attachment for preventing idle filling threads from entering cloth on a multiple shuttle loom, which may be either built into the loom as it is being originally constructed, or which may be sold as an attachment for a loom already in production.

In weaving cloth on a multiple shuttle loom having a lay and a multiple compartment shuttle box vertically reciprocatable up and down to a plurality of positions to bring selected respective compartments opposite an end of said lay for employing filling from the shuttle in the compartment then opposite the lay, whether employed on a pick and pick loom, multi-color loom, a double shuttle loom or other types of multi-compartment looms, employing any number of compartments actuated in the above manner, great difficulty has been experienced in having the threads from the shuttles in the respective compartments becoming loose and being carried a distance inwards of the selvage of the woven cloth by a shuttle from a vertically adjacent shuttle compartment. Thus after shifting shuttle compartments, the idle shuttles are either above or below the upper surface of the lay and have threads which extend to the selvage. These threads are likely to become entangled with a moving shuttle on the actuation thereof, which carrying of the threads from the idle shuttles into the woven cloth has often been called "trailing in" in the trade. This "trailing in" is the source of much trouble and damage to the woven material, with a loss of time and hence extra cost in the production of the cloth. Even if the "trailings in" be individually pulled out on a later inspection, unsatisfactory cloth still results.

Further objects of my invention relate to the specific structure of means I employ for this purpose, comprising thread gripping clasps attached to the inner end of each shuttle compartment to keep the thread from the idle shuttle contained therein in a taut condition as it extends to the selvage, positively preventing its entanglement, which thread gripping means are automatically released by suitable means for this purpose, carried by the lay as the respective shuttle compartment is raised or lowered into operative position opposite the end of the lay for the actuation of the shuttle therefrom, which means also functions to retain said thread gripping means in open position until its respective shuttle box compartment is moved away out of alignment with the end of the lay when the thread gripping means again takes effect to positively prevent a loose thread end which thus cannot become entangled

with threads from other then operating shuttles. An object of my invention, therefore, is to provide a device which will positively retain the thread ends from the respective idle shuttles in their respective compartments in a taut gripped position until it is again desired to use the shuttle from such respective compartment.

Further features of my invention relate to the construction of the specific means I preferably employ for this purpose.

These and such other objects of my invention as may hereinafter appear will be best understood from a description of an embodiment thereof, such as is shown in the accompanying drawings.

In the drawings,

Fig. 1 is a diagrammatic rear perspective view of one end of a lay having a four compartment movable shuttle box vertically reciprocatable thereon equipped with my invention and showing the lay adjacent its foremost beatup position immediately after laying a thread from a shuttle shown in #3 compartment, with the thread gripping means of my invention for the corresponding #3 compartment actuated to an open position.

Fig. 2 is a diagrammatic rear perspective view similar to Fig. 1, illustrating the shifting of the shuttle box and illustrating how, in accordance with my invention, the thread gripping means for the #3 shuttle box compartment pivots to a thread gripping position and the thread gripping means for the #2 shuttle box compartment is released as the shuttle box is moved downwards so that the shuttle in #2 compartment may become the active shuttle.

Fig. 3 is a diagrammatic rear perspective view exactly similar to Fig. 2 at the same portion of the stroke of the lay, but with the multiple shuttle box being raised to permit closing of the thread gripping means in the #1 compartment and to positively open the thread gripping means for the #2 compartment as the #2 compartment is being raised to active position in alignment with the lay so that its respective shuttle may become the active shuttle.

Fig. 4 is a diagrammatic rear perspective view similar to Figs. 1-3 with the lay moved to its extreme rearmost position adjacent which the shuttle from the #2 shuttle box compartment is urged by the picker stick across the lay and illustrating how the thread gripping means for said #2 shuttle box compartment is retained in an open position for the passing of the shuttle in and out of said #2 compartment.

Fig. 5 is a side elevation of the unit I prefer-

ably employ which may be attached to the front wall of the shuttle box having a plurality of thread gripping means constructed in accordance with my invention, vertically spaced from each other the normal distance between compartments, showing the wall of the shuttle box in dotted lines, and the movable jaw for #2 compartment in raised position in dotted lines.

Fig. 6 is a plan view of the attachment shown in Fig. 5.

Fig. 7 is a rear end elevation of a portion thereof carrying a single thread gripping means.

Fig. 8 is a perspective view of the cam plate I preferably employ for actuating the respective thread gripping means on the respective upper compartments and the means I preferably employ for vertically, horizontally and transversely adjustably mounting it on the outer end of the lay adjacent the movable shuttle box, illustrating it in substantially the position it assumes in the perspective views shown in Figs. 1-4.

In the drawings, wherein like characters of reference generally indicate like parts throughout, in order that my invention may be more clearly understood, I have diagrammatically illustrated certain portions of a multiple shuttle loom having a lay 10 and a multiple compartment shuttle box 12 vertically reciprocably mounted on one end thereof. As illustrated in Figs. 1-4, the lay is pivotally mounted and actuated by a suitable crank shaft (not shown) to pivot from its foremost position shown in Fig. 1 at which it beats up the just laid filling thread into position between the warp threads of the cloth, to its rearmost position shown in Fig. 4 adjacent which the picker stick (not shown) operates to throw the shuttle over the upper surface of the lay. The multi-compartment shuttle box 12 is vertically reciprocated to bring a selected #1^{sb}, 2^{sb}, 3^{sb} or 4^{sb} compartment containing respectively a #1^s, 2^s, 3^s or 4^s shuttle into alignment with the upper surface of the lay, said mechanism being controlled by the usual box chain mechanism which becomes effective to vertically shift the respective compartments, as shown in Figs. 2 and 3, substantially as said lay 10 is adjacent its rearmost position shown in Fig. 4. As stated hitherto, my invention is applicable to any type of a multi-shuttle loom having such a vertically reciprocable multi-shuttle compartment shuttle box. In the embodiment shown, I have illustrated it on a 4 x 1 multi-color loom, although if desired it may be employed in a pick and pick loom or a double shuttle loom in which there is a vertically reciprocable shuttle box on each end of the lay. My invention is applicable for use with a movable shuttle box employing any number of compartments and shuttles. As shown, the multiple compartment shuttle box 12 is vertically reciprocated immediately adjacent the end 24 of the lay by the rod 20 controlled by suitable mechanism (not shown).

In the operation of such a multiple compartment shuttle box loom the respective threads #1^t, 2^t, 3^t and 4^t are laid respectively from their respective shuttles to form the filling threads extending transversely of the cloth. When laid, these respective threads #1^t, 2^t, 3^t and 4^t are usually taut, but if a shuttle is loose in its respective compartment #1^{sb}, 2^{sb}, 3^{sb} or 4^{sb}, these respective threads #1, 2, 3 and 4 are apt to become loose both from movements caused by the vertically reciprocating movement of the shuttle box and shocks caused by the beatup movement of the lay and the takeup movement of the cloth.

In addition, as soon as any slack occurs in the filling, due to its twist it is apt to kink. Thus while the threads #1^t, 2^t, 3^t and 4^t respectively have tended to be taut when laid, before their respective shuttles are to be employed again, they are apt to become loose and get in the way of the other then active shuttles to be carried by the respective shuttles at least a distance laterally through the cloth inwardly of the selvage, causing the so-called objectionable "trailings in" hitherto referred to. The main object of my invention, as stated, is to positively retain these respective threads #1^t, 2^t, 3^t and 4^t in their taut position as laid until it is desired to use their respective shuttles again so that they will be positively held in a position out of the way of other respective active shuttles to positively prevent any "trailings in."

For this purpose I provide a thread gripping means adapted to extend between the end of the lay 10 and the inner end of each upper shuttle box compartment #1^{sb}, 2^{sb} and 3^{sb}, preferably mounted on the front wall of each compartment to extend between the outer end 24 of the lay and the inner end 30 of the shuttle box 12, releasable to permit movement of a shuttle to and from its respective compartment so that when the respective shuttles #1^s, 2^s and 3^s are being employed, said threads #1^t, 2^t and 3^t or any portion thereof will remain in a taut position, and I provide means 28 permanently mounted on said adjacent end 24 of the lay for releasing each respective thread gripping means 22¹, 22² and 22³ as its respective compartment #1^{sb}, 2^{sb} or 3^{sb} is brought into alignment with the upper surface 26 of the lay on said aforesaid up or down movements of said shuttle box, said means 28 being also capable of retaining a respective thread gripping means 22¹, 22² or 22³ in said open position, permitting movement of the shuttle 1^s, 2^s or 3^s from its respective compartment #1^{sb}, 2^{sb} or 3^{sb}, shown in Figs. 1-4, until said respective shuttle box compartment #1^{sb}, 2^{sb} or 3^{sb} is again vertically shifted to a different position in the manner shown in Figs. 2 and 3.

As stated, the thread gripping means and releasing means 28 may be constructed as an integral part of the loom in its initial manufacture, but I have shown in the drawings my invention comprising two pieces only adapted to be mounted as attachments on already existing looms. While the various thread gripping means 22¹, 22² and 22³ may be individually mounted on the inner end 30 of the multi-compartment shuttle box 12 immediately inwardly of their respective compartments #1^{sb}, 2^{sb} or 3^{sb}, I preferably mount the respective thread gripping means 22¹, 22² and 22³ on a common supporting means 32 so that the device may be attached as a unit to have the respective thread gripping means extend in proper relationship across the inner ends of their respective compartments #1, 2 and 3.

In the preferred embodiment shown, said supporting means 32 comprises a flat bar 32, in the embodiment shown comprising an L-bar having the base 34 and the L-arm 36. The base 34 is substantially the combined heights of the combined compartments #1^{sb}, 2^{sb}, 3^{sb} and 4^{sb} and is provided with suitable screw holes 38 so that the base 34 may be secured to the front wall 40 of the shuttle box 12 adjacent the inner end 30 thereof by suitable screws 42, or in any other suitable manner. In the embodiment shown, each thread gripping means comprises a stationary jaw and a movable jaw. In the embodiment

shown the three respective stationary jaws **44¹**, **44²** and **44³** for each respective upper compartment #**1^{sb}**, **2^{sb}** and **3^{sb}** are mounted on said supporting bar **32** at vertically spaced distances substantially the heights of the respective compartments #**2^{sb}** and **3^{sb}** to extend when said bar **32** is attached to said shuttle box respectively transversely interior of the inner end of each respective shuttle box compartment immediately below the level of each respective bottom wall **48¹**, **48²** and **48³** thereof. Each movable jaw **46¹**, **46²** and **46³** is pivotally mounted as at **50** to pivot into thread gripping relationship with its respective jaw **44¹**, **44²** or **44³**. In order to prevent each respective thread #**1^t**, **2^t** or **3^t** from becoming entangled with its pivot **50**, each stationary jaw may be provided with a guide arm **52** projecting upwardly from the inner edge thereof of adjacent the front end thereof near said pivot **50**. If desired, each stationary arm may be transversely grooved to provide a trough **54** to provide a bend **55** in each respective thread as it is being gripped for the more effective gripping thereof (see Fig. 7). In the embodiment shown, each stationary arm comprises a separate member soldered, riveted or otherwise secured to the forwardly projecting arm **36** of said bar **32**. Substantially adjacent the front end of each stationary arm I provide the pair of pivot ears **56** and **58**. The outer pivot ears of each pair comprise the lugs **58** individually projecting integrally forwardly from the base **34** which are bent forwardly to extend at a spaced distance from the portion of the arm **36** opposite thereto which forms the opposite respective ear **58** out of a portion of said arm **36**. Said respective ears **56** and **58** are provided with the respective pivot holes **62** and **64** horizontally aligned with each other. The pivot pin **50** is loosely mounted within said pivot holes **62** and **64** to pivot therein. Each cooperating movable thread gripping sheet metal jaw **46¹**, **46²** or **46³** is rigidly mounted on the inner end of said pivot pin **50** and has an arm **66** projecting forwardly and downwardly from said pivot pin **50** having an actuating pin **68¹**, **68²** or **68³** projecting laterally therefrom, which in the embodiment shown has the roller **70** pivotally mounted thereon. As means to urge the movable jaw into thread gripping relationship with the stationary jaw, I provide the coil spring **72** surrounding said pivot pin **50** between said ears **56** and **58**, having the extended inner end thereof abutting said base **34** and its outer end rigidly secured to said pivot pin **50** in any suitable manner, such as by the set screw **74**. It is apparent, however, that one end of the spring may be rigidly secured to any adjacent stationary part and the other end rigidly secured to any adjacent movable part to function to positively move the gripping jaw into gripping relationship with its respective stationary jaw to grip the respective thread #**1^t**, **2^t** or **3^t** therein, said stationary jaws and movable jaws thus forming thread gripping means.

The pivot pin **68¹**, **68²** or **68³** projecting laterally inwardly from the front end **66** of each respective movable jaw provides actuating means for moving said movable jaw away from gripping position with said stationary jaw, and I provide suitable means **28** effective to abut said pins **68¹**, **68²** or **68³** to raise said respective movable jaws **46¹**, **46²** or **46³** away from their respective stationary jaws **44** as the shuttle box **12** is vertically shifted to bring a selected compartment thereof opposite the end **26** of the lay for the actuation of its respective shuttle. For this purpose, in the embodiment shown, I employ the cam plate **28** preferably vertically, horizontally and transversely adjustably mountable on the front wall **76** of said lay adjacent the upper surface thereof at the multiple shuttle box end thereof so as to provide the rear cam edge **78** projecting between said outer end **24** of the lay and the inner end **38** of said movable shuttle box **12** in the path of vertical reciprocation of said movable jaw actuating pins **68¹**, **68²** and **68³**. Said cam plate **28** has a rear edge having a concave upper portion **80** and a convex lower portion **82**, said portion **80** being adapted to contact a respective actuating pin **68¹**, **68²** or **68³** on the downward movement of said shuttle box **12** and said portion **82** being adapted to contact a respective actuating pin **68¹**, **68²** or **68³** on the upward movement of said shuttle box **12**, to raise the respective movable jaws **46¹**, **46²** or **46³** of the compartment #**1^{sb}**, **2^{sb}** or **3^{sb}** being brought adjacent the end of said lay as said shuttle box **12** is raised or lowered to bring said respective desired compartment #**1^{sb}**, **2^{sb}** or **3^{sb}** into alignment with the upper surface **26** of the lay. Said cam **78** is also provided with an intermediate flat dwell portion **84** adapted when said shuttle box compartment #**1**, **2** or **3** is brought into the position shown in Fig. 4 at the end of the forward stroke of the lay to continue to contact its respective pin **68** to retain its respective movable jaw **46¹**, **46²** or **46³** in raised position, permitting movement of the respective shuttle to and from its respective compartment for the desired number of throws of the shuttle to or from the aligned compartment until said respective shuttle box is again reciprocated up or down to a different position.

While said cam means **28** may be vertically, horizontally and transversely adjustably mountable on the front wall **76** of said lay adjacent the upper surface thereof at a multiple shuttle box end thereof in any suitable manner, in the embodiment shown I preferably construct it of the following parts for this purpose. I provide an adjusting L-bar **86** adapted to have one arm **88** thereof projecting upwardly, said arm being provided with a vertical slot **90** extending downwardly from the upper end thereof adapted to adjustably receive a bolt **92** therein, as shown in Fig. 3, for the vertical adjustment thereof and securing thereof to the front wall **76** of the lay adjacent the upper surface thereof at said multiple shuttle box end thereof, and a lower arm **94** projecting forwardly from the lower end of said vertical arm **88** having a plurality of horizontally aligned vertically adjustable bolts **96** projecting upwardly from the upper surface thereof. I also provide a supplemental adjusting L-bar **98** having a base **100** having a horizontal slot **102** projecting outwardly from the inner end thereof for adjustably receiving said bolts **96** therein for horizontal adjustment relative to the outer end **24** of the lay **10**, and an arm **104** projecting upwardly from the outer end thereof having the vertically spaced horizontal slots **106** therein projecting forwardly from the rear edge thereof, and I provide the cam plate **108** having the vertically aligned inwardly projecting bolts **110** on the front end thereof horizontally adjustable within said slots **106** for the transverse adjustment of the rear cam surface **78** thereof between the outer end **24** of the lay and the inner end **38** of said shuttle box. In the actual embodiment shown, while I employ the word "bolts" to describe the members **92**, **96** and **110**, in the actual embodiment shown these comprise locking set screws adjustable within threaded holes therefor in their inter-engaging

members. It is thus obvious that vertical adjustment of said cam means 28 is provided by vertical movement of the slot 90 of said L-bar arm 83 relative to said bolt 92, that horizontal adjustment of said cam means is provided by horizontal movement of the slot 102 relative to said bolts 96 and that transverse adjustment of said cam means is provided by transverse adjustment of the locking bolts 110 in the slots 106. The flat dwell portion 84 of the cam 28 is essential in order that the movable jaw 46 of the respective compartment may be retained open for free passage of the shuttle across the lay to and from the aligned compartment.

I have illustrated in Fig. 1 the position the parts assume when after shuttle #3^s has been thrown from the opposite shuttle box across the surface of the lay, the lay has been moved forward to beat up the just laid thread #3^t into the woven fabric 114. It may be seen in this instance how the dwell portion 84 of the cam abuts the pin 68³ to retain the gripping finger 46³ in a raised open position, permitting free movement of a shuttle in and out of #3^{sb} compartment.

Fig. 2 illustrates the shifting from a #3 to a #2 compartment by lowering the shuttle box 12 as the lay 10 is adjacent the end of its forward stroke. In this position it will be seen that the thread gripping means 46³ for the #3 compartment has been released by the cam 78 permitting the spring 72 to urge it to closed position to grip its respective thread #3, and that the gripping means 22² for the #2 compartment is being opened as the #2 compartment has its bottom wall 48² brought into alignment with the top surface 26 of the lay, the upper surface 80 of the cam 78 abutting the pin 68² to cause it to raise its respective gripping jaw 48² until the mid position of the lay is reached on its backward stroke, as shown in Fig. 4, when the respective bottom wall 48² of the #2 compartment is brought into alignment with the top wall 26 of the lay and the pin 68² has been forced rearwards to abut the dwell portion 84 of the cam to retain the gripping jaw 48² in a completely raised open position, permitting passage of a shuttle in and out of compartment #2 and back and forth across the lay 10, as indicated in Fig. 4 until the shuttle box is again shifted to bring a different compartment into alignment with the upper surface of the lay.

Fig. 3 illustrates the shuttle box 12 being raised from the position making compartment #1^{sb} the effective compartment to a position making compartment #2^{sb} the effective compartment, as the lay approaches the mid portion of its backward stroke, in this instance the convex portion 82 of the cam surface abutting the pin 68² to pivot the gripping jaw 48² to the raised open position shown in Fig. 4, the cam surface 80 having in the meanwhile left the pin 68¹ to permit the spring 72 to close the gripping jaw 46¹. Also as the shuttle box is further raised to the position shown in Fig. 4 at the completion of the rearmost stroke of the lay, the pin 68² will again abut the flat portion 84 of the cam so as to retain the gripping jaw 48 in open position, permitting the passage of the shuttle to and from its respective compartment in the manner previously explained until the shuttle box is again shifted. It is thus apparent that as the shuttle box is raised to permit a respective lower compartment thereon to be brought into alignment with the upper surface 26 of the lay that the cam

surface 82 will contact its respective pin 68 to actuate its respective gripping means 22, as shown in Fig. 3, and that as the shuttle box 12 is respectively lowered to bring an upper compartment into alignment with the lay, the cam surface 80 will abut the respective pin 68 to release its respective gripping means 22 to permit passage of its respective shuttle from its respective compartment. It will be apparent, however, that as each gripping means is ineffective only when it is being moved to or retained in an open position, as shown in Figs. 2, 3 and 4, that only one gripping means can be released at a time so that my improved device will positively retain the other respective threads #1^t, 2^t or 3^t in a taut condition as they extend from the selvage 116 of the fabric being woven to the respective shuttles #1^s, 2^s or 3^s so that they will positively be out of the way of any lower shuttle in its passage across the lay, thus preventing said lower shuttle from striking them and "trailing" them in the fabric being woven. No thread gripping means 22 are needed for the shuttle in the lowermost compartment, as I have found out from experimentation that only lower shuttles can "trail in" to the fabric the respective threads from higher shuttles.

It is apparent, therefore, that I have provided a novel attachment for preventing "trailings in" which may be either constructed as an integral part of the loom or which may be sold as a separate attachment for looms already in operation, with the advantages described above.

It is understood that my invention is not limited to the specific embodiment shown and that various deviations may be made therefrom without departing from the spirit and scope of the appended claims.

What I claim is:

1. In a device for preventing idle filling threads from entering cloth woven on a multiple shuttle loom having a lay and a multiple compartment shuttle box vertically reciprocable up and down to a plurality of positions to bring a selected respective compartment opposite an end of said lay, thread gripping means having a portion fixedly mounted relative to each upper shuttle box compartment and a portion movably mounted relative to said fixedly mounted portion to retain threads from shuttles contained therein and extending to the selvage of the cloth being woven in a taut condition during actuation of said loom, and means for moving said movably mounted portion out of thread gripping relationship with the fixedly mounted portion of said thread gripping means only when its respective compartment is brought into alignment with the upper surface of the lay on said respective up and down movements of said shuttle box and to retain said respective thread gripping means for said compartment in alignment with the upper surface of said lay in open position permitting movement of the shuttle to and from said respective aligned compartment until the shuttle box is again reciprocated to a different position.

2. In a device for preventing idle filling threads from entering cloth woven on a multiple shuttle loom having a lay and a multiple compartment shuttle box vertically reciprocable up and down to a plurality of positions to bring a selected respective compartment opposite an end of said lay, thread gripping means having a portion fixedly mounted on the inner end of each upper shuttle box compartment and a portion movably

mounted relative thereto releasable from thread gripping engagement with said fixedly mounted portion to permit movement of a shuttle to and from its respective compartment and means carried by the lay for releasing each thread gripping means as its compartment is brought into alignment with the upper surface of the lay on said respective up and down movements of said shuttle box and to retain said thread gripping means in open position permitting movement of the shuttle to and from said respective compartment until the shuttle box is again reciprocated to a different position.

3. In a device for preventing idle filling threads from entering cloth woven on a multiple shuttle loom having a lay and a multiple compartment shuttle box vertically reciprocable up and down to a plurality of positions to bring a selected respective compartment opposite an end of said lay, a thread gripping clasp for each compartment comprising a grooved sheet metal stationary jaw rigidly mounted on the shuttle box to extend transversely interior of the inner end of its shuttle box compartment immediately below the level of the bottom wall thereof having a guard arm projecting upwardly from the inner edge thereof adjacent the front end thereof, and a cooperating movable thread gripping sheet metal jaw pivotally mounted on a pivot pin mounted on ears mounted to project forwardly from the front wall of said shuttle box having an arm projecting forwardly and downwardly from said pivot pin having an actuating pin projecting laterally therefrom, and a coil spring having one end fixed to said pivot pin and an opposite fixed end normally urging said movable jaw into gripping contact with said stationary jaw, and flat cam means mounted on said lay to project between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position permitting movement of the shuttle to and from said respective compartment until the shuttle box is again reciprocated to a different position.

4. In a device for preventing idle filling threads from entering cloth woven on a multiple shuttle loom having a lay and a multiple compartment shuttle box vertically reciprocable up and down to a plurality of positions to bring a selected respective compartment opposite an end of said lay, a thread gripping clasp for each compartment comprising a stationary jaw rigidly mounted on the shuttle box to extend transversely interior of the inner end of its shuttle box compartment immediately below the level of the bottom wall thereof, and a cooperating movable thread gripping jaw pivotally mounted on a pivot pin mounted on ears mounted to project forwardly from the front wall of said shuttle box having an arm projecting forwardly and downwardly therefrom having an actuating pin projecting laterally therefrom, and spring means normally urging said movable jaw into gripping contact with said stationary jaw, and flat cam means mounted on said lay to project between the end of said lay and said movable shuttle box

in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position.

5. An attachment for use in preventing idle filling threads from entering cloth woven on a multiple shuttle loom having a lay and a multiple compartment shuttle box vertically reciprocable up and down to a plurality of positions, successively bringing selected respective compartments opposite an end of said lay, thread gripping means for each upper shuttle box compartment each having a portion fixedly securable adjacent its respective compartment and a portion movable into juxtaposition therewith to retain threads from shuttles contained therein and extending to the selvage of the cloth being woven in a taut condition during actuation of said loom, and means securable to the loom for releasing said thread gripping means only when its respective compartment is brought into alignment with the upper surface of the lay on said respective up and down movements of said shuttle box and to retain said respective thread gripping means for said compartment in alignment with the upper surface of said lay in open position permitting movement of the shuttle to and from said respective aligned compartment until the shuttle box is again reciprocated to a different position.

6. An attachment for use in preventing idle filling threads from entering cloth woven on a multiple shuttle loom having a lay and a multiple compartment shuttle box vertically reciprocable up and down to a plurality of positions, successively bringing selected respective compartments opposite an end of said lay, comprising thread gripping means having a portion fixedly securable to the inner end of each upper shuttle box compartment and a portion movably mounted relative thereto, releasable to permit movement of a shuttle to and from its respective compartment and means attachable to the lay for releasing each thread gripping means as its compartment is brought into alignment with the upper surface of said lay on said respective up and down movements of said shuttle box and to retain said thread gripping means in open position permitting movement of the shuttle to and from said respective aligned compartment until the shuttle box is again reciprocated to a different position.

7. An attachment for use in preventing idle filling threads from entering cloth woven on a multiple shuttle loom having a lay and a multiple compartment shuttle box vertically reciprocable up and down to a plurality of positions, successively bringing selected respective compartments opposite an end of said lay comprising thread gripping clasp means for each compartment mountable on the inner end of each shuttle box compartment having a movable portion movable to a position permitting movement of a shuttle to and from its respective compartment having an actuating pin projecting later-

ally therefrom, an adjusting L-bar having a slot in one arm thereof adapted to adjustably receive a bolt therein for securing thereof to the front wall of the lay adjacent the upper surface thereof at a multiple shuttle box end thereof and a plurality of horizontally aligned vertically extending adjusting bolts projecting upwardly from the other arm thereof, a supplemental adjusting L-bar having a base having a horizontal slot for adjustably receiving said adjusting bolts therein for horizontal adjustment relative to the end of the lay and an arm projecting upwardly therefrom having vertically spaced horizontal slots projecting forwardly therein from the rear edge thereof, and a cam plate having vertically aligned bolts on the front end thereof horizontally adjustable within said slots and a rear cam edge projecting between the end of said lay and said movable shuttle box in the path of vertical reciprocation of said movable portion actuating pins having a rear edge having a concave upper portion and a convex lower portion adapted to contact a respective actuating pin to move its respective movable portion for a respective compartment as said shuttle box is respectively raised or lowered to bring said respective compartment into alignment with the upper surface of the lay and an intermediate dwell portion to retain said movable portion in a position permitting movement of the shuttle to and from said respective compartment until the shuttle box is again reciprocated to a different position.

8. An attachment for use in preventing idle filling threads from entering cloth woven on a multiple shuttle loom having a lay and a multiple compartment shuttle box vertically reciprocable up and down to a plurality of positions, successively bringing selected respective compartments opposite an end of said lay comprising thread gripping clasp means for each compartment mountable on the inner end of each shuttle box compartment having a movable portion movable to a position permitting movement of a shuttle to and from its respective compartment having an actuating pin projecting laterally therefrom, and a cam plate vertically, horizontally and transversely adjustably mountable on the front wall of the lay adjacent the upper surface thereof at a multiple shuttle box end thereof having a rear cam edge projecting between the end of said lay and said movable shuttle box in the path of vertical reciprocation of said movable portion actuating pins having a rear edge having a concave upper portion and a convex lower portion adapted to contact a respective actuating pin to move its respective movable portion for a respective compartment as said shuttle box is respectively raised or lowered to bring said respective compartment into alignment with the upper surface of the lay and an intermediate dwell portion to retain said movable portion in a position permitting movement of the shuttle to and from said respective compartment until the shuttle box is again reciprocated to a different position.

9. An attachment for use in preventing idle filling threads from entering cloth woven on a multiple shuttle loom having a lay and a multiple compartment shuttle box vertically reciprocable up and down to a plurality of positions, successively bringing a selected respective compartment opposite an end of said lay comprising a thread gripping clasp for each compartment comprising a grooved sheet metal stationary jaw rigidly mountable on the shuttle box to extend

transversely interior of the inner end of its shuttle box compartment immediately below the level of the bottom wall thereof having a guard arm projecting upwardly from the inner edge thereof adjacent the front end thereof, and a cooperating movable thread gripping sheet metal jaw pivotally mounted on a pivot pin mounted on ears mountable to project forwardly from the front wall of said shuttle box having an arm projecting forwardly and downwardly from said pivot pin having an actuating pin projecting laterally therefrom, and a coil spring having one end fixed to said pivot pin and an opposite fixed end normally urging said movable jaw into gripping contact with said stationary jaw, and flat cam means mountable on said lay to project between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position.

10. An attachment for use in preventing idle filling threads from entering cloth woven on a multiple compartment shuttle box vertically reciprocable up and down to a plurality of positions, successively bringing a selected respective compartment opposite an end of said lay comprising a thread gripping clasp for each compartment comprising a stationary jaw rigidly mountable on the shuttle box to extend transversely interior of the inner end of its shuttle box compartment immediately below the level of the bottom wall thereof and a cooperating movable thread gripping jaw pivotally mounted on a pivot pin mounted on ears mountable to project forwardly from the front wall of said shuttle box having an arm projecting forwardly and downwardly therefrom having an actuating pin projecting laterally therefrom, and spring means normally urging said movable jaw into gripping contact with said stationary jaw, and flat cam means mountable on said lay to project between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position.

11. An attachment for use in preventing idle filling threads from entering cloth woven on a multiple shuttle loom having a lay and a multiple compartment shuttle box vertically reciprocable up and down to a plurality of positions, successively bringing a selected respective compartment opposite an end of said lay comprising a thread gripping clasp for each compartment com-

prising a stationary jaw rigidly mountable on the shuttle box to extend transversely interior of the inner end of its shuttle box compartment immediately below the level of the bottom wall thereof and a cooperating movable thread gripping jaw pivotally mounted on a pivot pin mounted on ears mountable to project forwardly from the front wall of said shuttle box having an arm projecting forwardly and downwardly therefrom having an actuating pin projecting laterally therefrom, and spring means normally urging said movable jaw into gripping contact with said stationary jaw, an adjusting L-bar having a slot in one arm thereof adapted to adjustably receive a bolt therein for securingment thereof to the front wall of the lay adjacent the upper surface thereof at the multiple shuttle box end thereof and a plurality of horizontally aligned vertically extending adjusting bolts projecting upwardly from the other arm thereof, a supplemental adjusting L-bar having a base having a horizontal slot for adjustably receiving said adjusting bolts therein for horizontal adjustment relative to the end of the lay and an arm projecting upwardly therefrom having vertically spaced horizontal slots projecting forwardly therein from the rear edge thereof, and a cam plate having vertically aligned bolts on the front end thereof horizontally adjustable within said slots and a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position.

12. An attachment for use in preventing idle filling threads from entering cloth woven on a multiple shuttle loom having a lay and a multiple compartment shuttle box vertically reciprocable up and down to a plurality of positions, successively bringing a selected respective compartment opposite an end of said lay comprising a thread gripping clasp for each compartment comprising a stationary jaw rigidly mountable on the shuttle box to extend transversely interior of the inner end of its shuttle box compartment immediately below the level of the bottom wall thereof and a cooperating movable thread gripping jaw pivotally mounted on a pivot pin mounted on ears mountable to project forwardly from the front wall of said shuttle box having an arm projecting forwardly and downwardly therefrom having an actuating pin projecting laterally therefrom, and spring means normally urging said movable jaw into gripping contact with said stationary jaw, and a cam plate vertically, horizontally and transversely adjustably mountable on the front wall of the lay adjacent the upper surface thereof at the multiple shuttle box end thereof having a rear cam edge projecting between the end of said lay and said movable shuttle box in the path of vertical reciprocation of said movable jaw actuating pins having a rear edge having a concave upper portion and a convex lower portion adapted to contact a re-

spective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position.

13. An attachment for use in preventing loose ends in cloth woven on a multiple shuttle loom having a lay and a multiple compartment shuttle box vertically reciprocable up and down to a plurality of positions successively bringing selected respective compartments opposite an end of said lay, comprising a flat bar securable to the front wall of the shuttle box adjacent the inner edge thereof extending substantially the total height of the upper shuttle box compartments having a plurality of grooved sheet metal stationary jaws projecting rearwardly from the inner edge thereof to extend respectively transversely interior of the inner end of each respective shuttle box compartment immediately below the level of the bottom wall thereof, each having a guard arm projecting upwardly from the inner edge thereof adjacent the front end thereof, and pivot ears projecting forwardly therefrom substantially adjacent each stationary arm, a pivot pin pivotally mounted on each of said ears, a cooperating movable thread end gripping sheet metal jaw rigidly mounted on each pivot pin having an arm projecting forwardly and downwardly from said pivot pin having an actuating pin projecting laterally therefrom, coil spring means surrounding said pivot pin between said ears having an end abutting said bar and the other end fixed to said pivot pin normally urging said movable jaw into gripping contact with said stationary jaw, an adjusting L-bar having a slot in one arm thereof adapted to adjustably receive a bolt therein for securingment thereof to the front wall of the lay adjacent the upper surface thereof at the multiple shuttle box end thereof and a plurality of horizontally aligned vertically extending adjusting bolts projecting upwardly from the other arm thereof, a supplemental adjusting L-bar having a base having a horizontal slot for adjustably receiving said adjusting bolts therein for horizontal adjustment relative to the end of the lay and an arm projecting upwardly therefrom having vertically spaced horizontal slots projecting forwardly therein from the rear edge thereof, and a cam plate having vertically aligned bolts on the front end thereof horizontally adjustable within said slots and a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position vertically, horizontally and transversely adjustably mountable on the front wall of the lay adjacent

the upper surface thereof at the multiple shuttle box end thereof.

14. An attachment for use in preventing loose ends in cloth woven on a multiple shuttle loom having a lay and a multiple compartment shuttle box vertically reciprocable up and down to a plurality of positions to bring a selected respective compartment opposite an end of said lay comprising a flat bar securable to the front wall of the shuttle box adjacent the inner edge thereof extending substantially the total height of the upper shuttle box compartments having a plurality of stationary jaws projecting rearwardly from the inner edge thereof to extend respectively transversely interior of the inner end of each respective shuttle box compartment immediately below the level of the bottom wall thereof, and a cooperating movable thread end gripping jaw pivotally mounted on said bar substantially opposite a respective stationary jaw having an arm projecting forwardly and downwardly having an actuating pin projecting laterally therefrom, spring means normally urging said movable jaw into gripping contact with said stationary jaw, and a cam plate having a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position, vertically, horizontally and transversely adjustably mountable on the front wall of the lay adjacent the upper surface thereof at the multiple shuttle box end thereof.

15. An attachment for use in preventing loose ends in cloth woven on a multiple shuttle loom having a lay and a multiple compartment shuttle box vertically reciprocable up and down to a plurality of positions to bring a selected respective compartment opposite an end of said lay comprising a flat bar securable to the front wall of the shuttle box adjacent the inner edge thereof extending substantially the total height of the upper shuttle box compartments having a plurality of stationary jaws projecting rearwardly from the inner edge thereof to extend respectively transversely interior of the inner end of each respective shuttle box compartment immediately below the level of the bottom wall thereof, and a cooperating movable thread end gripping jaw pivotally mounted on said bar substantially opposite a respective stationary jaw having an arm projecting forwardly and downwardly having an actuating pin projecting laterally therefrom, spring means normally urging said movable jaw into gripping contact with said stationary jaw, and a cam plate having a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring

said respective compartment into alignment with the upper surface of the lay and an intermediate dwell portion to retain said movable jaw in raised position, permitting movement of the shuttle to and from said respective compartment until the shuttle box is again reciprocated to a different position, mountable on the front wall of the lay adjacent the upper surface thereof at the multiple shuttle box end thereof.

16. An attachment for use in preventing loose ends in cloth woven on a multiple shuttle loom having a lay and a multiple compartment shuttle box vertically reciprocable up and down to a plurality of positions to bring a selected respective compartment opposite an end of said lay comprising a flat bar securable to the front wall of the shuttle box adjacent the inner edge thereof extending substantially the total height of the upper shuttle box compartment having a plurality of grooved sheet metal stationary jaws projecting rearwardly from the inner edge thereof to extend respectively transversely interior of the inner end of each respective shuttle box compartment immediately below the level of the bottom wall thereof, each having a guard arm projecting upwardly from the inner edge thereof adjacent the front end thereof, and pivot ears projecting forwardly therefrom substantially adjacent each stationary arm, a pivot pin pivotally mounted on each of said ears, a cooperating movable thread end gripping sheet metal jaw rigidly mounted on each pivot pin having an arm projecting forwardly and downwardly from said pivot pin having an actuating pin projecting laterally therefrom, coil spring means surrounding said pivot pin between said ears having an end fixed to said bar and the other end fixed to said pivot pin normally urging said movable jaw into gripping contact with said stationary jaw, and a cam plate having a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position, vertically, horizontally and transversely adjustably mountable on the front wall of the lay adjacent the upper surface thereof at the multiple shuttle box end thereof.
17. An attachment for use in preventing loose ends in cloth woven on a multiple shuttle loom having a lay and a multiple compartment shuttle box vertically reciprocable up and down to a plurality of positions to bring a selected respective compartment opposite an end of said lay comprising a flat bar securable to the front wall of the shuttle box adjacent the inner edge thereof extending substantially the total height of the upper shuttle box compartments having a plurality of grooved sheet metal stationary jaws projecting rearwardly from the inner edge thereof to extend respectively transversely interior of the inner end of each respective shuttle box compartment immediately below the level of the bottom wall thereof, each having a guard arm

projecting upwardly from the inner edge thereof adjacent the front end thereof, and pivot ears projecting forwardly therefrom substantially adjacent each stationary arm, a pivot pin pivotally mounted on each of said ears, a cooperating movable thread end gripping sheet metal jaw rigidly mounted on each pivot pin having an arm projecting forwardly and downwardly from said pivot pin having an actuating pin projecting laterally therefrom, coil spring means surrounding said pivot pin between said ears having an end fixed to said bar and the other end fixed to said pivot pin normally urging said movable jaw into gripping contact with said stationary jaw, and a cam plate having a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position, mountable on the front wall of the lay adjacent the upper surface thereof at the multiple shuttle box end thereof.

18. An attachment for use in preventing loose ends in cloth woven on a multiple shuttle loom having a lay and a multiple compartment shuttle box vertically reciprocable up and down to a plurality of positions to bring a selected respective compartment opposite an end of said lay comprising a flat bar securable to the front wall of the shuttle box adjacent the inner edge thereof extending substantially the total height of the upper shuttle box compartment having a plurality of stationary jaws projecting rearwardly from the inner edge thereof to extend respec-

tively transversely interior of the inner end of each respective shuttle box compartment immediately below the level of the bottom wall thereof, and a cooperating movable thread end gripping jaw pivotally mounted on said bar substantially opposite a respective stationary jaw having an arm projecting forwardly and downwardly having an actuating pin projecting laterally therefrom, spring means normally urging said movable jaw into gripping contact with said stationary jaw, an adjusting L-bar having a slot in one arm thereof adapted to adjustably receive a bolt therein for securement thereof to the front wall of the lay adjacent the upper surface thereof at the multiple shuttle box end thereof and a plurality of horizontally aligned vertically extending bolts projecting upwardly from the other arm thereof, a supplemental adjusting L-bar having a base having a horizontal slot for adjustably receiving said adjusting bolts therein for horizontal adjustment relative to the end of the lay and an arm projecting upwardly therefrom having vertically spaced horizontal slots projecting forwardly therein from the rear edge thereof, and a cam plate having vertically aligned bolts on the front end thereof horizontally adjustable within said slots and a rear cam edge projecting between the end of said lay and said movable shuttle box in the path of vertical reciprocation of said movable jaw actuating pins having a rear edge having a concave upper portion and a convex lower portion adapted to contact a respective actuating pin to raise its respective movable jaw of a respective compartment as said shuttle box is respectively raised or lowered to bring said respective compartment into alignment with the upper surface of the lay and an intermediate dwell portion to retain said movable jaw in raised position, permitting movement of the shuttle to and from said respective compartment until the shuttle box is again reciprocated to a different position.

JOSEPH FRANCIS MUHEIM.
